UNITED STATES PATENT OFFICE.

CHARLES FRANCIS JENKINS, OF WASHINGTON, DISTRICT OF COLUMBIA.

FILM-PIERCING SPARK UNIT.

Application filed January 2, 1925. Serial No. 221.

This invention relates to apparatus for receiving radio photographic messages, and has for its principal object a simple and effective means for making the record.

5 With this and other objects in view the invention consists of the novel combination of elements herein disclosed and particularly pointed out in the claim.

10 In the drawings Figure 1 is an elevation, and Figure 2 a top view with a diagram of the wiring to the radio receiving set.

15 In the drawings A is a threaded shaft upon which is a wide faced gear B engaged by a worm C on the motor shaft. D is a metal cylinder also on the shaft A, carrying thereon a sheet of paper D'. E is a spark point, one terminal of a suitable transformer F, the other terminal of which is attached to the shaft support G. The primary of the transformer is attached to a 20 radio receiving set H.

When radio signals are received there is a spark discharge between the point E and

the metal cylinder D, which spark passing through the paper would perforate it, making a matrix from which prints could be made. If the order of the radio signals represented the letters of a message, then the sparks would perforate a matrix which would print a copy of the original letter. 25 Or if the paper was also light sensitive, a photo record would appear. If the sensitive surface were on metalized paper the photo record only would remain, no perforating resulting.

30 35 What I claim is—

The combination of a rotating cylinder, a threaded shaft to rotate and to advance said cylinder, a wide-faced gear for rotating said shaft, said gear having a face equal to the longitudinal movement of said shaft.

40 In testimony whereof I have affixed my signature.

CHARLES FRANCIS JENKINS.
